Henry, Reeves & Wagner, LLP(57) **CLAIM**

The ornamental design for a circular saw bracket as shown and described herein.

DESCRIPTION

For a more complete understanding of the present disclosure, the objects and ornamentation thereof, reference is now made to the ensuing descriptions taken in connection with the accompanying drawings described as follows.

FIG. 1 is a perspective view of the circular saw bracket, according to an example of the present disclosure.

FIG. 2 is a left side elevational view of the circular saw bracket, according to an example of the present disclosure.

FIG. 3 is a perspective view of the circular saw bracket in use, according to an example of the present disclosure. Features shown in broken lines in FIG. 3 are for illustrating the environmental structure, e.g., the circular saw and the structure to which the circular saw bracket may mount, and form no part of the claimed design.

The present design is a circular saw bracket for hanging a circular saw. The circular saw bracket includes a body and a ledge which protrudes outwardly from the body. A lip protrudes upwardly from an end of the ledge.
